HAND BRUSH OR THE LIKE

Joseph Vallis, 448 Spadina Road, Toronto,
Ontario, Canada

Filed Aug. 29, 1960, Ser. No. 61,917

Term of patent 14 years

(Cl. D9—2)

Fig. 2.

Fig. 1.

Fig. 3.

Fig. 1 is a side elevational view of a hand brush or the like showing my new design;

Fig. 2 is an end elevational view; and

Fig. 3 is a top plan view thereof.

The dominant features of my design reside in the portions shown in full lines.

The design of the non-illustrated end and side of the brush are substantially like the end and side, respectively, of the brush as shown in Figures 1 and 2.

I claim:

The ornamental design for a hand brush or the like, as shown and described.
